MACHINE FOR ASSEMBLING SHOE PARTS

Herbert J. Willmott, Beverly, Mass., assignor to
United Shoe Machinery Corporation, Flemington, N. J., a corporation of New Jersey

Application February 21, 1941, Serial No. 380,031

19 Claims. (Cl. 12—42)

This invention relates to the assembling of shoe-parts as, for example, the forcing upon nails projecting from the heel-seat of a shoe, a heel drilled with nail-receiving passages, this being according to the method set forth in Letters Patent of the United States No. 2,200,385, Eich, May 14, 1940.

An object of my invention is to effect such assembling operations as that above indicated, by the application to the work of ample pressure by simple and durable means readily controllable by the operator, and without danger of injury to him or to the machine. To this end and in a novel manner, I combine with a cylinder, to which fluid-pressure is applied, and a piston movable within it, a shoe-support carried by the piston and an abutment arranged to retain a shoe-part against assembling pressure upon actuation of the piston. Both the work-support and abutment are preferably adjustable as to their normal vertical and angular positions, to best adapt them to the requirements of the operator. In attaching heels to shoes, I provide relative movement between a cylinder and piston, and mount upon the movable element a support adapted to receive contact of the cone of a last within a shoe being operated upon, a co-operating abutment being engaged by a heel to be attached. Regardless of whether fluid-pressure power means is employed, I utilize a member movable by the operator to control the application of a relatively small preliminary force by the power means to the pressure mechanism, and a second member, also movable by the operator, to produce a greater assembling force. The first permits adjustment of the work under light retaining pressure and safe manipulation by the operator, while the second completes the operation. To prevent damage to the machine by excessive movement of the shoe-support and consequent contact with the opposed abutment, as when no shoe is in place upon said support, means is provided for cutting off fluid pressure from the actuating cylinder before such contact occurs. The preferred arrangement of fluid-pressure mechanism involves the compact mounting together, in a liquid-container formed in the base of the machine, of the power-cylinder and its piston, a valve-casing formed with the cylinder, a pump and a manifold attached to the cylinder, and having passages through which connections between the associated elements are made.

In the accompanying drawings,

Fig. 1 shows a particular embodiment of this invention in perspective;

Fig. 2 is an enlarged broken front elevation, especially illustrating the hydraulic mechanism;

Fig. 3, a similar side elevation; and

Fig. 4, a full horizontal section on the line IV—IV of Fig. 3.

The frame of the machine includes an enclosed base-portion 10, from the rear of a cover 11 for which rises an arm 12 curved forwardly to overhang the base. Formed in the base is a container 14, which may be filled to a level indicated at 1 in Fig. 2, with some such liquid as oil. The container may be drained through a plugged opening at 11. Secured to the bottom of the container is a vertical cylinder 16, having preferably integral with it a casing 18 of a valve V. In the cylinder a piston 20 is arranged to reciprocate, the rod 22 of the piston being continued by an extension 24 splined to a sleeve 26. The sleeve is attached to the cover 11 by a clamp 27, so that it is adjustable both longitudinally of and angularly about its vertical axis. Upon the upper extremity of the rod-extension is an enlargement 28, on which is mounted a work-support 30. This support may generally be the same as that disclosed in Letters Patent of the United States No. 2,223,474, Willmott, December 3, 1940, it being arranged to rock at 32 upon the enlargement and having beneath it a layer 34 of yieldable material; but the upwardly projecting last-pin of the patent is preferably omitted and there left free an upper surface 36. This surface may receive contact of the crown 38 of the cone of a last L, so that a shoe S upon the last may be freely positioned laterally. Clamped at 38 in the arm 12 of the frame is a sleeve 40, adjustable similarly to the sleeve 27 and carrying at its lower extremity an abutment A for engagement with a heel H to be attached to the shoe upon the support 30. This abutment, with its adjustable yieldable tread-plate 42 and rear fork 44 having a yieldable covering, may be in every essential particular similar to the corresponding device which appears in Letters Patent of the United States No. 2,200,386, Eich, May 14, 1940.

Mounted in the container 14 adjacent to the top of the cylinder 16 is a pump 46, which may be of the gear-type for creating hydraulic pressure. Upon the shaft 48 of the pump is a pulley 50, driven through a belt 52 by a motor 54 carried upon the machine-frame above the cover 11. Pump-pressure in the cylinder 16 and exhaust from said cylinder are controlled by a valve-

plunger 56, movable longitudinally of the casing 18. This plunger has a lower enlargement 58 and an upper enlargement 60, which may open and close the respective ports 62 and 64. The ports 62 may be caused by the valve-enlargement 58 to either join the cylinder 16 below the piston 20 to an exhaust-opening 66 to the container 14, or through the valve-casing 18 to a pressure-opening 68 therein. The ports 64, when left open by the enlargement 60, divert pump-pressure from the interior of the casing 18 through a discharge-passage 80 into the container. When the ports 64 are closed, such pressure is exerted through the casing and the open ports 62 to act upon the piston 20. To cause this shutting off of the discharge to be gradual, with a like increase in the force applied to the piston, the ports 64 are shown in Fig. 2 as having their sides converging downwardly. They are also placed opposite each other at points removed from the passage 80 to give a balanced effect. Attached to the rear of the cylinder is a manifold 70, within which are formed passages piped at 72 to the outlet of the pump 46 and at 74 to the pump-inlet. Further, there is a screened intake-opening at 76 from the container 14, a delivery-opening registering with the opening 68 of the valve-casing, and an opening at 78 (Fig. 3) communicating with the casing 79 of a relief-valve v . The valve-casing 18 has a discharge-passage 80 to the container. A pressure-gage g may be connected to the hydraulic system at 81 (Fig. 4).

The stem of the valve-plunger 56 is linked at 82 to a lever 84, fulcrumed at 86 upon the top of the container 14. The opposite end of the lever is joined by a rod 88 to a treadle-lever 90, fulcrumed at 92 at the bottom of the frame. The foot-pad of the treadle is held normally raised against an adjustable stop 94 by a tension-spring 96. This positions the valve-plunger as appears in Fig. 2, the cylinder 16 below the piston 20 being initially open to the container at 62, 66. The pump now takes in liquid from the container through the opening 76 and the connecting manifold-passage to the pipe 74, wasting through the pipe 72, manifold-passage to the casing-opening 68, port 64 and passage 80, back to the container. This circuit for the pump is indicated by the heavy dotted arrows in Fig. 2. The piston receives no pressure and is at rest, it having been lowered by gravity after the previous operation, with the liquid exhausting at 62, 66. Depression of the treadle will draw down the valve-plunger to close the exhaust-connection from the cylinder and the waste-connection at 64, 80, at the same time joining the interior of the valve-casing through the ports 62 to the cylinder. Now, the pump-pressure is diverted from the waste-connection, and is exerted from the opening 68, as shown by the heavy dashed arrows, through the interior of the valve-casing and the port 62 in the cylinder 16. This elevates the piston with the support 30, so the work thereon is lifted and urged against the abutment A. When the machine is not in operation, inverted U-passages 98, 98 in the manifold 70 and communicating with the pump-connections 72 and 74, trap bodies of liquid and keep said pump primed.

The force applied to the work may be limited by the relief-valve v , as shown by the light dotted lines in Fig. 2, the admission-opening 78 from the manifold to this valve being connected to the path of the pressure-liquid by a branch-

passage. Within the casing 79 of the valve v is guided for vertical movement in its lower portion a tubular plunger 100, closed at the upper end to normally prevent discharge through a casing-passage 102 and open at the lower end for communication with the opening 78. The plunger is held down to maintain openings 104 through the plunger-wall normally closed, by an expansion-spring 106 interposed between the top of the plunger and an abutment 108 guided for vertical adjustment in the upper portion of the casing. Threaded into the abutment is a screw 110, rotatable in the valve-cover and joined to a rod 112, the upper extremity of which turns in a bracket 114. This bracket is secured adjustably to the base-cover 11 to allow the rod 112 to be aligned vertically. The rod is connected by sprocket-gearing 118 to a short vertical shaft 120 rotatable in a bushing 122, passing through a slot in the bracket 114 and through the cover 11 and held in place by a nut 123 threaded upon the bushing above the cover. A flange 124 upon the bushing gives support for the bracket 114 and clamps it in its adjusted position. By rotating the shaft 120 through a hand-wheel 126 fast upon its upper end, the rod 112 and screw 110 may be turned to raise or lower the abutment 108. This will vary the force of the spring 106, and thus the point at which the pump-pressure will lift the plunger 100 and blow off through the passage 102.

It is desirable to bring the work upon the support 30 into engagement with the abutment A, and apply to it a preliminary pressure such that the work-parts may be correctly located for assembly and there held until a greater final assembling pressure is applied. To obtain this result, there passes through an opening in the lever 84, between the link 82 and the fulcrum 86, a rod 128 guided in a sleeve 130 secured to the underside of the frame-cover 11 (Fig. 3). The rod is held normally raised by an expansion-spring 132, surrounding it between the sleeve and nuts 134 threaded upon the upper extremity. These parts are protected by a cover 136. A collar 138 fast upon the rod limits its upward movement by engagement with the lower end of the sleeve. This positions a washer, resting upon stop-nuts 140 threaded upon the lower portion of the rod, at a definite height, at which, when engaged by the lever, it will stop the descent of the valve-plunger 56. The movement of the plunger, thus determined, will partially close the upper exhaust-ports 64 of the valve v , and similarly open the ports 62 to apply pump-pressure to the cylinder 16, as already pointed out. Greater movement of the valve-plunger under the influence of the treadle is prevented by a latch 142, pivoted upon the sleeve 130 and engaging the underside of the collar 138. A link 144 unites the tail of the latch to a lever 146, which is fulcrumed upon the frame-arm 12 and may be of U-shape, extending across the frame at the rear of the support 30, so it may be readily accessible to either of the operator's hands (Fig. 1). A tension-spring 148 joining an arm from the rear of the lever 146 to the frame maintains normal engagement of the latch with the collar. The operator, being ready for the assembling action of the machine, forces down the lever 146. This withdraws the latch from the stop-collar, and upon further depression of the treadle the spring 132 yields, so the lever 84 continues to lower the valve-plunger 56. The ports 64 and 62 are, respectively, fully closed and opened for the appli-

cation to the work of pump-pressure, limited only by the setting of the relief-valve v .

It will be evident that, unless means were furnished to prevent it, upon depression of the treadle when there is no work in place upon the support 30, said support would be forced against the abutment A to perhaps cause breakage. This I guard against by securing upon the piston-rod 22, above the top of the cylinder 16, a collar 150, which may be clamped in a chosen vertical position, and is of sufficient diameter to project beneath the forward extremity of the lever 84. The location of the collar is such that, when the travel of the work-support has exceeded to safe distance, it strikes the lever, lifting this against the pressure of the operator's foot upon the treadle, to cut off pressure from the cylinder and stop the movement of the work-support.

In the use of the machine, the operator, taking in one hand a lasted shoe S in the heel-seat of which nails N have been inserted with shank-portions projecting outwardly, applies to the nails a heel drilled with passages to register with them, and places the end of the last-cone upon the supporting surface 36. The relation between the tread-plate 42 and the rear fork 44 of the abutment A will have been adjusted for proper engagement with the particular form of heel which is to be attached. At this time, with the plunger 56 of the valve V raised, the constantly operating pump 46 is forcing liquid from the frame-container 14 idly through the passages of the manifold 70 and the ports 64 of the valve, back to the container through the discharge-passage 80 of the valve; see the path indicated in Fig. 2 by the heavy dotted arrows. The operator then actuates the treadle 90, lowering the valve-plunger to an extent determined by the latched stop 140, to close partially the valve-port 64 and similarly open the port 62. A low pressure is set up in the cylinder 16 below the piston 20, through the valve-casing from the pressure-opening 68 along the path of the heavy dashed arrows, some pump-exhaust continuing through the passage 80. This lifts the support 30, and, as the heel comes in contact with the abutment A, the operator may shift the last-cone over the surface 36 to bring said heel into correct retaining engagement. The force exerted is not such as to firmly clamp the work, or to injure the operator's hands if they are caught between the work and the abutment. With the work thus located, the operator frees the stop 140 from the latch 142 by actuation of the lever 146, and further depresses the treadle. Now, the valve-plunger is carried to a position at which full assembling pressure is applied to the work, to force the nails N into the heel-passages and urge the cup of the heel firmly against the heel-seat of the shoe. During this action, the yieldability of the work-support 30, and of the tread-plate 42 and the covering of the rear fork 44 of abutment A, allows these elements to more perfectly adapt themselves to the angle of the crown of the last and contour of the heel being attached. The force exerted upon the work is limited by the blowing off of pressure into the container 14 through the passage 102 of the relief-valve v , as shown by the light dotted arrows. Rotation of the hand-wheel 126, with resulting variation in the force of the spring 106 of the valve v enables the operator to control the assembling pressure. When the treadle is freed by the operator and the valve-plunger 56 is raised by the treadle-spring 96, pressure is cut off from the cylinder 16, and the path for waste from

the pump through the discharge-passage 80 re-established. Simultaneously, exhaust from the cylinder is opened to the container at 62, 66, as shown by the light dashed arrows. In absence of work from the support, actuation of the lever 84 by the piston-rod-collar 150, after a predetermined time or extent of ascent, will arrest the travel of said support before it strikes the abutment A. The piston, with the parts which it carries, falls by gravity, and the completed work may be removed from the support. Through the piston a contracted passage 152 is shown, this permitting the escape from below the piston of any air which may have entered, as during the supply of oil. No harm is done by the release of the pressure-liquid from below the piston, this merely moving back and forth in negligible quantities through the passage as the piston reciprocates. A baffle-ring 154, carried by the piston along the passage, prevents jets of the liquid from being thrown through the open top of the cylinder. By clamping the sleeve 26 of the work-support 30 at 27 and the sleeve 40 of the abutment A at 38, both of these devices may be varied in position about and along their vertical axes, which extend in the direction of pressure-movement. Thus the work may be presented at a normal or initial height and angle most convenient for the operator. In the adjustment of the work-support, the piston 20 by which it is carried reciprocates between different extremes of travel in the cylinder-space, but always between the port 62 and opening 68. As the normal vertical position of the work-support is changed, the location of the collar 150 upon the piston-rod 22 is correspondingly altered.

Having described my invention, what I claim as new and desire to secure by Letters Patent of the United States is:

1. In a machine for assembling shoe-parts, a cylinder, means for applying pressure within the cylinder, a piston movable in the cylinder by such pressure, a shoe-support carried by the piston, an abutment arranged to retain a shoe-part against assembling pressure upon actuation of the piston, and means arranged to vary the normal vertical positions of both the work-support and abutment.

2. In a machine for assembling shoe-parts, a cylinder, means for applying pressure to the cylinder, a piston movable in the cylinder, a shoe-support carried by the piston, an abutment arranged to retain a shoe-part against assembling pressure upon actuation of the piston, and means arranged to vary the normal angular positions of the work-support and abutment about axes extending in the direction of pressure-movement.

3. In a machine for attaching heels to the heel-seats of lasted shoes, a cylinder and co-operating piston, means for introducing fluid-pressure into the cylinder to produce relative movement between it and the piston, a support carried by the movable element and adapted to receive contact of the cone of a last within a shoe being operated upon, an abutment for engagement with a heel to be attached to the shoe, and means arranged to vary the normal vertical and angular positions of the shoe-support and heel-abutment.

4. In a machine for attaching heels to the heel-seats of lasted shoes, a cylinder and co-operating piston, means for introducing fluid-pressure into the cylinder to produce relative movement between it and the piston, a support carried by the movable element and having a surface over

which the cone of a last within a shoe may be shifted to different operating positions, and an abutment provided with heel-engaging members variable in position to adapt them for contact with heels differing in form.

5. In a machine for attaching heels to the heel-seats of lasted shoes, a cylinder and co-operating piston, means for introducing fluid-pressure into the cylinder to produce relative movement between it and the piston, a support carried by the movable element and having a surface over which the cone of a last within a shoe may be shifted to different operating positions, and an abutment provided with heel-engaging members variable in position to adapt them for contact with heels differing in form, the shoe-support and heel-engaging members being yieldable upon application of attaching pressure.

6. In a machine for assembling shoe-parts, pressure mechanism comprising a shoe-support and an abutment co-operating with the support and arranged to retain a shoe-part against pressure, the support and abutment being relatively movable for the application of such pressure, power means, a member movable by the operator to control the application of a relatively small preliminary force by the power means to the pressure mechanism, and a member movable by the operator to control the application of a greater assembling force to the pressure mechanism.

7. In a machine for assembling shoe-parts, pressure mechanism comprising a shoe-support and an abutment co-operating with the support and arranged to retain a shoe-part against pressure, the support and abutment being relatively movable for the application of such pressure, power means, a member movable by the operator to control the application of force by the power means to the pressure mechanism, means for limiting the extent of movement of the controlling member and thereby the amount of force applied to the pressure mechanism, and a member movable by the operator to render the limiting means ineffective and the controlling member movable to a greater extent to increase the force applied to the pressure mechanism.

8. In a machine for assembling shoe-parts, a cylinder and co-operating piston, said cylinder and piston being relatively movable, a shoe-support carried by the movable element, an abutment arranged to retain a shoe-part against assembling pressure, means for applying fluid-pressure to the cylinder to create preliminary engagement between the shoe and shoe-part, and means for increasing the fluid-pressure in the cylinder to effect the assembly.

9. In a machine for attaching heels to the heel-seats of lasted shoes, a cylinder and co-operating piston, fluid-pressure means connected to the cylinder to produce relative movement between it and the piston, a shoe-support carried by the movable element, an abutment for engagement with a heel to be attached to the shoe, a valve by which the fluid-pressure in the cylinder is controlled, a member movable by the operator to open the valve, a stop for limiting the movement of the member and the extent to which the valve may be opened, and a member movable by the operator to render the stop ineffective.

10. In a machine for attaching heels to the heel-seats of lasted shoes, a cylinder and co-operating piston, fluid-pressure means connected to the cylinder to produce relative movement between it and the piston, a shoe-support carried by the movable element, an abutment for en-

gagement with a heel to be attached to the shoe, a valve by which the fluid-pressure in the cylinder is controlled, a treadle movable by the operator to open the valve, a yieldable stop limiting movement of the treadle, a latch for retaining the stop in its movement-limiting position, and a lever movable by the operator to release the latch.

11. In a machine for assembling shoe-parts, a cylinder and co-operating piston, said cylinder and piston being relatively movable, a shoe-support carried by the movable element, an abutment arranged to retain a shoe-part against assembling pressure, means for applying fluid-pressure to the cylinder to carry the shoe-support toward the abutment, and means for cutting off fluid-pressure from the cylinder at a predetermined time before the shoe-support contacts with the abutment.

12. In a machine for assembling shoe-parts, a cylinder and co-operating piston, said cylinder and piston being relatively movable, a shoe-support carried by the movable element, an abutment arranged to retain a shoe-part against assembling pressure, means for creating fluid-pressure in the cylinder, a valve for controlling such fluid-pressure, and means controlled in the movement of the shoe-support for closing the valve.

13. In a machine for assembling shoe-parts, a cylinder, a piston movable therein, a shoe-support carried by the piston, a fixed abutment arranged to retain a shoe-part against assembling pressure upon actuation of the piston, fluid-pressure means connected to the cylinder, a valve by which the fluid-pressure in the cylinder is controlled, a member movable by the operator to open the valve, and a member movable by the piston to close said valve after a definite travel of the piston.

14. In a machine for assembling shoe-parts, a cylinder, a piston movable therein, a shoe-support carried by the piston, a fixed abutment arranged to retain a shoe-part against assembling pressure upon actuation of the piston, fluid-pressure means connected to the cylinder, a valve by which the fluid-pressure in the cylinder is controlled, a treadle, and a lever connected to the treadle and to the valve, an element movable with the piston and arranged to engage the lever.

15. In a machine for assembling shoe-parts, a cylinder, a piston movable therein, a shoe-support carried by the piston, a fixed abutment arranged to retain a shoe-part against assembling pressure upon actuation of the piston, fluid-pressure means connected to the cylinder, a valve by which the fluid-pressure in the cylinder is controlled, a treadle, a lever connected to the treadle and to the valve, and a collar variable in position upon the piston and arranged to engage the lever.

16. In a machine for assembling shoe-parts, pressure mechanism comprising a shoe-support and an abutment co-operating with the support and arranged to retain a shoe-part against pressure, the support and abutment being relatively movable for the application of such pressure, power means, a member movable by the operator to control the application of a relatively small preliminary force by the power means to the pressure mechanism, a member movable by the operator to control the application of a greater assembling force to the pressure mechanism, and means for limiting the extent of movement of the pressure mechanism to a predetermined extent.

17. In a machine for assembling shoe-parts, a

frame having a base-portion furnishing a liquid-container, a cylinder provided with a valve-casing mounted in the liquid in the container, a piston movable in the cylinder, a valve-plunger movable in the casing, a pump mounted in the container, a manifold attached to the cylinder and provided with passages connected to the inlet and outlet of the pump, to the opposite extremities of the valve-casing and to the container, a shoe-support carried by the piston, an abutment arranged to retain a shoe-part against assembling pressure, and means arranged to move the valve-plunger.

18. In a machine for assembling shoe-parts, a frame having a base-portion furnishing a liquid-container, a cylinder provided with a valve-casing mounted in the liquid in the container, a piston movable in the cylinder, a valve-plunger movable in the casing, a pump mounted in the container, a manifold attached to the cylinder and provided with passages connected to the inlet and outlet of the pump, to the opposite extremities of the valve and to the container, a pressure-

limiting valve joined to a manifold-passage between the pump and the valve-casing, a shoe-support carried by the piston, an abutment arranged to retain a shoe-part against assembling pressure, and means arranged to move the valve-plunger.

19. In a machine for assembling shoe-parts, a frame having a base-portion furnishing a liquid-container, a cylinder provided with a valve-casing mounted in the liquid in the container, a piston movable in the cylinder, a valve-plunger movable in the casing, a pump mounted in the container, a manifold attached to the cylinder and provided with passages connected to the inlet and outlet of the pump, to the opposite extremities of the valve-casing and to the container, the inlet- and outlet-passages being of inverted U-form, a shoe-support carried by the piston, an abutment arranged to retain a shoe-part against assembling pressure, and means arranged to move the valve-plunger.

HERBERT J. WILLMOTT.
